CANISTER PROVIDED WITH RIP-WIRE
OPENING DEVICE

Peter Bogner, Oxford, England, assignor to Saml.
Hanson & Son, Limited, London, England, a
British company

Application February 15, 1941, Serial No. 379,085
In Great Britain February 13, 1940

12 Claims. (Cl. 220—49)

This invention is for improvements in or relating to canisters provided with rip-wire opening devices, and is concerned more particularly with canisters used for containing foodstuffs.

One object of the invention is to provide a canister with a rip-wire opening device in such a way as not to interfere substantially with the normal method of closing the canister and at the same time to facilitate the maintenance of the rip-wire in a desired location in which it is not exposed to the contents of the canister.

Another object is to facilitate opening the canister by means of the rip-wire.

A further object is to provide a seamed canister having a rip-wire for cutting a sufficiently large opening in the end-closure of the canister to permit removal of the contents, with the rip-wire so mounted as not to be exposed to the contents of the canister and not to interfere substantially with the function of the seam securing the end closure to the canister body.

With these objects in view the invention consists in providing a canister formed with a wire-receiving fold extending along the boundary of a portion of the canister that is to be movable when the canister has been opened to permit removal of the contents, and a rip-wire disposed in said fold, with the side walls of the fold pressed together in such manner that the rip-wire is indented into the material of said walls. The pressing together of the walls of the wire-receiving fold serves to maintain the rip-wire in its desired location and also assists in isolating the rip-wire from exposure to the contents of the canister since the rip-wire is almost completely surrounded by the walls of the fold. Further, the material of the canister is strengthened by the pressing together of said side-walls, so that the adjoining portions of the canister on opposite sides of the fold behave substantially as if they were formed in one continuous piece without the fold although they are separable after ripping has occurred. The indentation of the rip-wire into the material of the said walls causes the formation of one or more lines of weakening along which the canister may be readily torn open by means of the rip-wire.

The aforesaid fold may be formed in the material of the end-closure or in the material of the body of the canister in such manner as to extend around the latter.

Certain preferred forms of construction in accordance with the invention are illustrated in the accompanying drawing and will now be described by way of example.

In the drawing,

Figure 1 is a broken elevation view showing portions of the body and end-closure of a seamed canister, with the fold containing the rip-wire formed in the end-closure adjacent to the seam and around a shoulder surrounding the usual central depression in the end-closure;

Figures 2 and 3 are views similar to Figure 1, showing modified constructions in which the form of the shoulder is changed;

Figure 4 is a view similar to Figure 1, showing a further modification in which no shoulder is provided;

Figure 5 is a view similar to Figure 1, showing yet another modification in which the fold containing the rip-wire is formed in the material of the body of the canister;

Figure 6 is a perspective view on a scale smaller than that of Figure 1, showing part of the upper end of the canister of Figure 1 including the end portions of the fold through one of which the rip wire protrudes to the outside of the canister, part of the body and end closure being broken away to show the sections through these parts, and

Figure 7 is a detail view showing a modified formation of the fold near its end portions, as it appears before the rip-wire is inserted and the side walls of the fold are pressed together.

Like reference numerals indicate like parts throughout the drawing.

In Figure 1 the body of the canister is indicated at 10 and the end-closure at 11. The end of the body 10 is formed with the usual seaming flange 12 which is interfolded with a marginal seaming flange 13 formed on the end closure 11. The latter is formed in known manner with a central depression whereof the bottom and side walls are indicated at 14 and 15 respectively. The material of the end closure 11, which like the body 10 is of sheet metal, is continued outwardly from the central depression 14, 15 in the form of an upwardly- and outwardly-inclined narrow shoulder 16 extending around the central depression. Between the shoulder 16 and the marginal flange 13 there is formed in the material of the end-closure a fold 17 extending substantially around the shoulder 16 and having side walls 18 and 19 which are pressed together throughout the depth of the fold. In effect the fold 17 constitutes an upstanding bead. The rip-wire is indicated at 20 and it will be seen that it is interposed between the side walls 18 and 19, is spaced from the extremities of the bead provided by the fold 17, and, due to the pressing together of said walls, 55 is indented into the material of them to form

thin places 21 and 22 constituting lines of weakening extending along the sides of the fold 17 throughout the length of the fold. In other words, the rip-wire 20 is embedded in the fold 17 and is disposed between locations above and below it at which the side walls 18 and 19 are pressed into engagement with one another.

The fold 17 defines the boundary of a portion of the canister which is to be movable to permit removal of the contents when the canister is opened. The said movable portion of the canister comprises the central depression 14, 15, the narrow shoulder 16 and part of the wire bearing fold 17. Since these parts have a radial extent greater than the internal radius of the body 10, no inwardly-projecting parts such as might impede removal of the contents of the canister are left when the said movable portion is moved away from the body of the canister. The actual extent of the said movable portion is of course determined by the line of ripping.

As will be seen from Figure 6 the fold 17 does not extend completely around the end closure 11, but is made discontinuous at one place to form a gap 23. The fold has sloping end walls 24 and 25 at opposite ends of the gap, and the end wall 24 is formed with an aperture, as indicated at 26 in Figure 7, through which one end of the rip-wire 20 projects to the outside of the canister. The aperture is displaced from the material adjoining the fold 17 in an outward direction, that is to say, along the depth of the fold, so that the pressing together of the side walls 18 and 19 of the fold will not tend to split the sheet metal in the neighbourhood of the end wall 24 as might occur if the aperture extended up to the material adjoining the fold. The outward displacement of the said aperture also facilitates sealing the space between the inserted rip-wire and the edge of the aperture, as well as helping to avoid exposure of the aperture to the contents of the canister. The projecting end of the rip-wire may be bent inwardly as shown at 27 and formed with a loop 28 which may be anchored by solder or the like 29 to the central portion of the end closure 11. The other end of the rip-wire 20 may conveniently be left inside the canister since the wire 20 is gripped along its whole length between the side walls 18 and 19 of the fold. The other end wall 25 of the fold at the gap 23 may have only a slight inclination to the general plane of the end-closure as shown in full lines, due to the pressing together of the walls 18 and 19, or it may be somewhat steeper as shown in chain lines, the latter being the initial form of the end wall 25 before the walls 18 and 19 are pressed together.

To open the canister, the projecting end of the rip-wire 20 is pulled away from the centre of the end-closure and drawn away from the longitudinal centre line of the canister. A rod, pencil or the like may be inserted in the loop 28 to secure a purchase on the wire when pulling it outwardly away from the canister. The pull on the wire will rip the material of the end-closure along the outer line of weakening 22. When the material has been ripped along the whole length of the fold 17, the movable part of the end closure will only be connected to the body 10 by the material at the gap and this material will serve as a hinge about which the movable portion of the end-closure may pivot in moving away from the body 10.

Pulling of the rip-wire as described above, to

tear the closure along the outer line of weakening 22, will leave a portion of the closure 14, i. e., the part of fold 17 above the line 22, accessible on the exterior of the canister and readily available to give the user a good grip on the closure so it may be easily removed.

The end closure 11, before being seamed to the body 10 of the canister, is conveniently constructed as described in my co-pending application Serial No. 351,619 filed 6th August 1940, and the method and apparatus set forth in my co-pending application Serial No. 322,748 filed 7th March 1940, may be employed in the manufacture of the end closure. The closure 11 may be seamed to the body 10 by means of the apparatus described and claimed in my co-pending application Serial No. 192,989 filed 28th February 1938 on which issued Patent No. 2,250,002. Preferably a gasket 30 of sealing composition is interposed between the marginal flange 13 of the end-closure and the seaming flange 12 of the body to assist in ensuring that the seam is airtight, and the gasket 30 may be continued across the line of engagement between the walls 18 and 19 of the fold, indicated at 31 in Figure 1.

Figures 2 and 3 illustrate modified constructions which correspond closely with that of Figure 1 except that the narrow shoulder formed around the central depression in the end closure is modified in shape, and a corresponding modification is made in the shape of the portion of the body 10 against which the shoulder engages. In Figure 2 there is shown a shoulder 32 which is inclined downwardly and outwardly from the central depression 14, 15, that is to say, the shoulder is inclined oppositely to the shoulder 16 of Figure 1. The adjacent portion of the body 10 is forced into the recess below the shoulder as indicated at 33, so that there is a firm engagement between the shoulder 32 and the portion 33 of the body 10. In Figure 3 the shoulder instead of being inclined is made flat as shown at 34 and it engages with a portion 35 of the body 10 which is more or less flattened to ensure firm engagement with the shoulder 34. The constructions of Figures 2 and 3 also differ from that of Figure 1 in that the shoulders 32 and 34 are of a straight formation as viewed in cross-section, while the shoulder 16 of Figure 1 is of arcuate form in cross-section.

In the modification illustrated in Figure 4 the wire-receiving fold is shown at 36 and it includes side walls 37 and 38 which are pressed together similarly to the walls 18 and 19 of Figure 1 to enclose the rip-wire 20. Instead of being separated by a shoulder from the central depression 14, 15 of the end-closure, the fold 36 has its side-wall 37 formed as a direct continuation of the wall 15 of the central depression. As in the first-described constructions the fold is disposed above the seam and the marginal flange 13 extends from the outer wall 38 of the fold. Thin places 21 and 22 are formed as in Figures 1 to 3 by the pressing together of the walls 37 and 38 causing the rip-wire 20 to be indented into the material of said walls. In the construction of Figure 4 the pressing together of the walls 37 and 38 of the fold 36 below the rip-wire 20 may be sufficient to isolate the rip-wire from exposure to the contents of the canister, or, as an additional measure for this purpose, the sealing gasket 30, which is shown as stopping short of the nip 39 between the walls 37 and 38, may be continued inwardly to cover the nip 39. The nip 39 may also be covered by lac-

quer such as is usually employed to cover the interior of canisters for foodstuffs.

To protect it against accidental damage, the fold 36 may, if desired, be bent downwardly from the position shown.

The modified construction shown in Figure 5 differs from the constructions of the preceding figures in that the wire-containing fold indicated at 40 is formed in the material of the body 10 instead of in the material of the end-closure 11 of the canister. The fold 40 is formed on the outside of the body and has opposed portions or side-walls 41 and 42 which are pressed together, with a rip-wire 20 between them, in such manner as to indent the rip-wire into the material of the walls 41 and 42 and form thin places 43 and 44 constituting lines of weakening corresponding to those shown at 21 and 22 in Figures 1 to 4. The construction of Figure 5 is particularly applicable to a canister having a seamless body. In this case the fold 40 may be made continuous so as to extend completely around the body 10 and an aperture may be formed in one of the opposed portions or walls 41 and 42 for the passage of one end of the rip-wire 20 to the outside of the canister. Alternatively the fold may be completely interrupted as shown in Figure 6, or reduced in depth as described later in connection with Figure 7, to form end-walls one of which is apertured for the passage of one end of the rip-wire to the outside of the canister. With the fold completely interrupted as aforesaid the construction of Figure 5 may be applied to a canister whereof the body has a longitudinal seam, the latter being arranged to pass through the gap formed by the interruption of the fold 40.

In the construction of Figure 5 a lacquer coating may be applied so as to bridge the nip 45 between the opposed walls 41 and 42 of the fold in order to supplement the effect of the pressing together of said walls in preventing exposure of the rip-wire 20 to the contents of the canister. The lacquer covering the nip 45 may form part of the usual lacquer coating applied to the interior of the body 10. Further the fold 40 may be bent over, if desired, in a fashion similar to that described in connection with the fold 36 of Figure 4, so as to lie against the neighbouring portion of the body 10. The fold 40 is preferably disposed as near as may be convenient to the seam 12, 13 while being sufficiently displaced therefrom to avoid interference with the operation of seaming the end-closure 11 to the body 10, and in this case the fold may be bent over in the direction away from the seam.

Figure 7 shows a modified formation of the fold in which, instead of being completely interrupted to form a gap 23 as in Figure 6, the fold 17 is reduced in depth as shown at 46. For clearness, Figure 7 shows the fold before insertion of the wire and before its side-walls have been pressed together, and it will be seen that between the reduced portion 46 and the portions of the fold that are of maximum depth inclined end-walls 47 and 48 are formed. The aperture 26 is formed in the end-wall 41 and is thus displaced outwardly from the material of the canister adjoining the fold 11, so as to secure the advantage previously described.

It will be appreciated that the invention provides an improved form of canister embodying a rip-wire opening device with the rip-wire held securely in the desired location for its proper operation and also prevented from being exposed to the contents of the canister. The improved con-

struction is moreover susceptible of being produced in large quantities quickly and cheaply. In the constructions of Figures 1 to 4, the pressing together of the side walls of the fold ensures a new and improved co-action between the end-closure 11 and body 10, because the material of the end-closure in the neighbourhood of the fold is made more rigid, with the portions of the material on opposite sides of the fold behaving substantially as if they were direct continuations of one another, as viewed in cross-section. This permits the formation of a seam which is somewhat tighter than would otherwise be possible in a construction embodying the rip-wire, and, what is even more important, increases the pressure exerted between the end-closure and the body at locations between the rip-wire and the interior of the canister. The shoulders 16, 32 and 34 of Figures 1 to 3, by pressing against the end of the body 10, each form a seal, as described in my co-pending application Serial No. 191,230, filed February 18, 1938, serving to isolate the rip-wire 20 from exposure to the contents of the canister. In the present improved forms of construction the increased rigidity of the material in the neighbourhood of the fold causes the pressure, and therefore the effectiveness, of such seal to be increased. Similarly, in the construction of Figure 4, the pressure exerted between the side-wall 15 of the central depression and the interior of the end of the body 10 is increased by the greater rigidity of the material in the neighbourhood of the fold.

It is to be understood that the invention is not restricted to the precise constructional details shown in the drawing.

I claim:

1. A canister comprising a body, an end-closure secured to said body, a fold extending around the canister and including side-walls formed in one of the parts constituted by the body and end-closure to define the boundary of a portion of the canister which is to be movable to permit removal of the contents when the canister is opened, and a rip-wire contained in said fold, with the side-walls of the fold pressed together sufficiently to indent the rip-wire into the material of said side-walls for substantially the length of the rip wire.
2. In a canister comprising a body, an end-closure secured to said body, and means for ripping the canister open along a line contained in one of the parts constituted by the body and end-closure, the combination of a fold formed in the material of the canister and extending along said line of ripping and including side-walls which are pressed together throughout the depth of the fold, and a rip-wire interposed between said side-walls and indented into the material thereof.
3. In a canister of the rip-opening type comprising a body and an end-closure secured to said body, and having on one of the parts constituted by the body and end-closure a line of ripping bounding a portion of the canister which is to be movable to permit removal of the contents when the canister is opened, the combination of a closed fold extending around the canister and including side-walls formed in the material of the canister along the line of ripping, and a rip-wire interposed between and gripped by said side-walls and indented into the material thereof to weaken said material along the line of ripping, said side walls being in contact with each other on opposite sides of the wire.

4. A canister comprising a body, an end-closure secured to said body, a fold extending around the canister and including side-walls formed in one of the parts constituted by the body and end-closure to define the boundary of a portion of the canister which is to be movable to permit removal of the contents when the canister is opened, with said side-walls pressed into engagement with one another at locations spaced apart in the direction of the depth of the fold, and a rip-wire contained in said fold and disposed between said spaced locations of engagement of said side-walls and indented into the material of said side-walls.

5. In a canister comprising a body, an end-closure secured to said body, and means for ripping the canister open along a line contained in the end-closure, the combination of a fold formed in the material of the end-closure adjacent to and around the periphery thereof and extending along the line of ripping and including side-walls which are pressed together throughout the depth of the fold, and a rip-wire interposed between said side-walls and indented into the material thereof.

6. In a canister of the type comprising a body having a seaming flange thereon and an end-closure formed with a central depression fitting within the body and a marginal seaming flange interfolded with the seaming flange on the body, the combination of a fold formed in the material of the end-closure to extend substantially around said central depression between the latter and the marginal seaming flange and including side-walls which are pressed together throughout the depth of the fold, and a rip-wire contained in said fold and indented into the material of the side-walls thereof.

7. In a canister of the type comprising a body having a seaming flange thereon and an end-closure formed with a central depression fitting within the body and a marginal seaming flange interfolded with the seaming flange on the body, the combination of a shoulder formed in the material of the end-closure around the central depression and between said depression and the marginal seaming flange for co-operation with the seaming flange on the body, a fold including side-walls formed in the material of the end-closure to extend substantially around said shoulder between the latter and the marginal seaming flange and a rip-wire contained in said fold, with the side-walls of the fold pressed together throughout the depth of the fold sufficiently to indent the rip-wire into the material of said side-walls.

8. In a canister of the type comprising a body and an end-closure seamed to said body and formed with a central depression fitting within the body, the combination of an inclined shoulder formed in the material of the end-closure around said central depression and engaging with

the body, a closed fold upset in the material of the end-closure to extend substantially around said shoulder and including sides which are pressed together throughout the width of the fold, and a rip-wire embedded in said fold and indented into the material of the sides thereof.

9. In a canister of the rip-opening type comprising a body and an end-closure secured to said body, the combination of a closed fold formed in the material of one of the parts constituted by the body and end-closure to extend along the boundary of a portion of the canister which is to be movable to permit removal of the contents when the canister is opened, which fold is bent over on to the adjacent part of said material and includes opposed portions pressed together throughout the width of the fold, and a rip-wire embedded in said fold and indented into the material of the opposed portions of the fold.

10. In a canister of the rip-opening type comprising a body and an end-closure secured to said body, the combination of a closed fold formed in the material of the body and extending substantially around the latter on the outside thereof, which fold includes opposed portions pressed together throughout the width of the fold, and a rip-wire embedded in said fold and indented into the material of the opposed portions of the fold.

11. In a canister of the rip-opening type comprising a body and an end-closure secured to said body, the combination of a closed fold formed on the outside of the canister in the material of one of the parts constituted by the body and end-closure to extend substantially around the canister along the boundary of a portion thereof which is to be movable to permit removal of the contents when the canister is opened, which fold includes side-walls which are pressed together throughout the depth of the fold and end-walls whereof one is formed with an aperture displaced outwardly from the material adjoining the fold, and a rip-wire embedded in said fold for substantially the whole length thereof and indented into the material of the side-walls thereof and having an end projecting through the said aperture to the outside of the canister.

12. In a canister including a body and an end-closure secured thereto, a fold formed in the material composing one of said members, said fold including side-walls extending circumferentially of said one of said members and constituting an upstanding bead thereon, a rip-wire disposed between the walls of said fold and intermediate the top and bottom of the fold, said side-walls being in contact on opposite sides of the wire, and the wire being indented into the inner surfaces of said walls to form lines of weakening therein.

PETER BOGNER.
